UNITED STATES PATENT OFFICE.

HARRY M. WOOD, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

COMMUTATOR-CYLINDER.

1,289,344.

Specification of Letters Patent. Patented Dec. 31, 1918.

Application filed January 26, 1917. Serial No. 144,667.

To all whom it may concern:

Be it known that I, HARRY M. WOOD, a citizen of the United States, and a resident of Edgewood Park, in the county of Allegheny and State of Pennsylvania, have invented a new and useful Improvement in Commutator-Cylinders, of which the following is a specification.

My invention relates to the construction 10 of commutator cylinders for dynamo-electric machines, and it has for its object to provide a commutator cylinder that is particularly adapted for use in connection with dynamo-electric machines of the high-volt- 15 age type.

In the construction of commutator cylinders for high voltage, it is essential that sufficient insulation be provided in order to prevent electrical discharges between the 20 conducting segments which are at machine potential and the clamping rings of which are at ground potential. The obvious expedient is to increase the length of the "creepage path" which is usually defined as 25 the shortest distance over the exposed surfaces of the insulating material between the "live" parts and the ground. The desired results have heretofore been obtained by merely extending the insulation longitudinally 30 beyond the ends of the conducting segments, but, owing to the space limitations existing in certain types of apparatus, such as railway motors, this has not always been found practicable.

According to the present invention, I provide a high-voltage commutator cylinder having a safe creepage path wherein the overall length of the commutator cylinder is actually decreased, as compared with existing types. This result is obtained by the use of a novel form of clamping ring for the commutator segments that is provided with a projecting portion which extends above the engaging circumferential surfaces 45 of the clamping ring and of the segments for a greater distance than it extends beyond the ends of the segments. The layer of insulating material that is usually provided between the clamping ring and the 50 segments is extended beyond the ends of the segments and is supported by the projecting portion of the clamping ring.

In the accompanying drawings, Figure 1 is a transverse sectional view of a commutator cylinder embodying my invention, and

Figs. 2, 3 and 4 are fragmentary views similar to Fig. 1 showing modifications of my invention.

A plurality of conducting and insulating segments 1 and 2, respectively, are circumferentially arranged upon a supporting spider 3 and a clamping ring 4 that is provided with a V-shaped annular end face which engages a corresponding V-shaped groove provided in the segments 1 and 2 60 adapted to maintain the segments in position upon the spider 3 by means of bolts 5. The clamping ring 4 is further provided with a projecting portion 6 that extends laterally above the engaging circumferential 65 surfaces 1^a and 4^a of the segments and of the clamping ring. A layer 7 of insulating material is interposed between the commutator segments and the clamping ring 4 and is extended beyond the ends of the segments 70 to cover the adjacent surface of the projecting portion 6 of the clamping ring 4.

A modification of my invention is shown in Fig. 2 wherein the projecting portion 6 of the clamping ring 4 is provided with an 80 annular recess 8 within which is located a reinforcing ring 9 that is preferably composed of a hard and durable insulating material possessing considerable mechanical strength. In this modification, the projecting portion 6 need not be laterally extended 85 as far as shown in Fig. 1, because of the support given to the insulating layer 7 by the reinforcing member 9.

A further modification of my invention is 90 shown in Fig. 3 wherein the layer 7 of insulating material extends only to the base of the portion 6 and terminates in an external flange 10. A second layer 11 of insulating material covers the face of the projecting portion 6 and is provided with an internal flange 12 that fits within the flange 10 of the layer 7. The clamping ring 4 is provided with an annular groove 13 that is filled with a molded insulating material 14 95 in order to provide an effective seal against creepage through the joint between the layers of insulating material.

A still further modification of my invention is shown in Fig. 4 wherein the projecting portion 6 of the clamping ring is provided with a corrugated or wave-like surface 15 that is covered with an extended portion of the insulating layer 7.

While I have shown my invention in sev-

eral preferred forms, it is apparent that other constructions may be employed for providing an insulating surface extending laterally above the engaging circumferential surfaces of the commutator segments and clamping ring without departing from the spirit of my invention and I desire, therefore, that only such limitations shall be imposed thereon as come within the scope of the appended claims.

I claim as my invention:

1. A commutator cylinder comprising circumferentially arranged conducting and insulating segments, and a clamping ring therefor having an insulated portion projecting beyond the ends and above the outer surface of said segments.
2. A commutator cylinder comprising circumferentially arranged conducting and insulating segments, and a clamping ring therefor having a portion projecting beyond the ends and above the outer surface of said segments and a layer of insulating material covering said projecting portion.
3. A commutator cylinder comprising circumferentially arranged conducting and insulating segments, and a clamping ring therefor having a portion projecting laterally above the surface of said segments and a layer of insulating material covering said projecting portion.
4. A commutator cylinder comprising circumferentially arranged conducting and insulating segments, and a clamping ring therefor having a surface in spaced relation with an inner circumferential surface of said segments, the said ring being provided with a portion projecting beyond the ends of said segments and above the said surfaces,

and a layer of insulating material covering 40 said projecting portion.

5. A commutator cylinder comprising circumferentially arranged conducting and insulating segments, a clamping ring therefor having a surface in spaced relation with an 45 inner circumferential surface of said segments, the said ring being provided with a portion that projects above the said surfaces for a greater distance than it projects beyond the ends of said segments, and a layer 50 of insulating material covering said projecting portion.

6. A commutator cylinder comprising circumferentially arranged conducting and insulating segments, a clamping ring therefor 55 having a surface in spaced relation with an inner circumferential surface of said segments and a layer of insulating material interposed between said ring and said segments, the said insulating material being extended beyond and above the said surfaces of said segments and of said ring.

7. A commutator cylinder comprising circumferentially arranged conducting and insulating segments, a clamping ring therefor 65 having a surface in spaced relation with an inner circumferential surface of said segments, and a layer of insulating material interposed between said ring and said segments, the said insulating material projecting above the said surfaces for a greater 70 distance than it projects beyond the ends of said segments.

In testimony whereof, I have hereunto subscribed my name this nineteenth day of 75 January, 1917.

HARRY M. WOOD.
